UNITED STATES PATENT OFFICE.

BABETTE ABT, OF FRANKFORT-ON-THE-MAIN, GERMANY, ASSIGNOR TO
GUSTAV MENKE, OF SAME PLACE.

FILE FOR LOOSE SHEETS, PAPERS, &c.

SPECIFICATION forming part of Letters Patent No. 611,443, dated September 27, 1898.

Application filed January 22, 1898. Serial No. 667,542. (No model.)

To all whom it may concern:

Be it known that I, BABETTE ABT, residing at Frankfort-on-the-Main, Germany, have invented a certain new and useful Improved 5 File for Loose Sheets, Papers, and the Like, of which the following is a specification.

My invention relates to files, and has for its object to produce a form of construction in which loose sheets may be arranged in such a 10 manner as to allow of their easy inspection.

My invention will be understood by referring to the accompanying drawings, in which—

Figure 1 is a side elevation of a file embodying my invention. Fig. 2 is a plan view thereof. Fig. 3 is a side elevation looking in a direction at right angles to the direction of view in Fig. 1, and Fig. 4 is a plan view of the base of the file.

20 In the drawings, *a* is a loop of wire or rod bent into the form shown and serving as the base of the file. The free ends *a'* of the loop *a* are shown as turned up and preferably have their extreme ends *a''* bent out horizontally.

25 The upturned ends or uprights *a'* of the loop *a* may be provided on one or both sides with notches *a''*. A plate *b* slides upon the uprights *a'*, the said uprights passing through apertures in the said plate. The edges or

30 flanges *b'* of the plate *b* are turned down and receive the free ends *c'* of the lever *c*. This lever *c* is shown as consisting of a wire loop or frame having its free ends *c'* journaled in the flanges *b'* of the plate *b*. Another lever

35 or frame *d* is likewise journaled in the flanges *b'* of the plate *b* at the opposite side of the said plate from the side in which the lever *c* is pivoted or journaled. Thus it will be observed that the levers *c* and *d* are pivoted to

40 the plate *b* upon opposite sides of the uprights *a'*, so that when both of the levers or loops *c d* are swung down the plate *b* will be tilted and will engage in one of the notches *a''* of the uprights. The file may likewise be

45 provided with stiff separating-pieces or separatrices *r* in order to remove single sheets. One of the loops or levers *c d* is turned up, thus releasing the second loop and also simultaneously loosening the plate on the appara-

tus of the main loop or frame *a*. The two 50 loops and their plate *b* are then pushed upward either entirely or onto the horizontal bent parts of the uprights of the main loop or frame and in the latter case may form a support for sheets placed thereon.

It will be understood that the file so far as described is complete in itself; but in case it is desired to attach the same to a casing in order to assemble a number of files into a file-cabinet such object may be attained as follows: The frame or loop *a* may be secured to a plate *x*, whose edges *x'* are turned over the branches of the main loop *a*. The plate *x* may likewise be provided with fasteners *x''*, by which it may be fastened to a casing *y*.

Having described my invention, what I claim, and desire to secure by Letters Patent, is—

1. In a file for loose sheets and the like, the combination of the standards *a'*, the plate *b* 70 engaging the standards and the loops *c d* pivoted to the plate.

2. In a file for loose sheets and the like, the combination of the standards *a'*, the plate *b* and the loop *c* having its free ends pivoted in 75 the plate.

3. In a file for loose sheets and the like, the combination of the standards *a'*, the plate *b* and the levers *c d* pivoted to the said plate 80 on opposite sides of the said standards.

4. In a file for loose sheets and the like, the combination of the standards *a'*, the plate *b* engaging the standards and the loops *c d* pivoted to the plate, combined with a casing and means for securing the uprights *a'* to the 85 casing.

5. In a file for loose sheets and the like, the combination of the main loop *a* provided with uprights, the plate *b*, the levers *c d* pivoted to the plate on opposite sides of the uprights, 90 substantially as described and for the purposes set forth.

In witness whereof I have hereunto set my hand in presence of two witnesses.

BABETTE ABT.
